UNITED STATES PATENT OFFICE.

WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-DETECTING MECHANISM.

Application filed April 5, 1922. Serial No. 549,934.

To all whom it may concern:

Be it known that I, WALTER H. WAKEFIELD, a citizen of the United States, residing at Worcester, in the county of Worcester and State of Massachusetts, have invented a new and useful Weft-Detecting Mechanism, of which the following is a specification.

This invention relates to weft detecting mechanism of the movable plunger type, as shown in the prior patent of E. H. Ryon, No. 1,221,768, issued April 3, 1917.

In the weft detecting mechanism therein shown, a single yielding arm or tension member engages all of the detecting plungers, moving them normally to rearward position and being moved forward whenever any one of the plungers engages the bobbin in the shuttle or a substantial amount of weft thereon. When the tension arm is thus moved by one of the plungers, the remaining plungers are relieved of tension and are easily moved forward by the slightest pressure, as by engagement with one or two turns of weft on the bobbin.

It is evident, however, that substantial weft exhaustion should be indicated under such conditions and it is the general object of my invention to provide a certain resistance to the forward movement of the plungers, in addition to the yielding tension of the spring arm. The result of such provision is to make the indications by the plungers more reliable than has been heretofore attained.

My invention further relates to arrangements and combinations of parts which will be hereinafter described and more particularly pointed out in the appended claims.

A preferred form of my invention is shown in the drawings in which—

Fig. 1 is a left hand side elevation of weft detecting mechanism embodying my improvements;

Fig. 2 is a front elevation thereof;

Fig. 3 is a plan view thereof;

Fig. 4 is a plan view of the cover plate and friction device; and

Fig. 5 is a sectional elevation taken along the line 5—5 in Fig. 4.

Referring to the drawings, I have indicated a portion of an arm 10 adapted to be rigidly supported by the loom frame (not shown) and having an eccentric stud or

bushing 11 adjustably mounted therein. A support 12 is provided with a split bearing 13 adapted to be clamped about the eccentric stud 11. Set screws 14 at the lower end of the arm or bracket 10 engage a lug 15 on the support 12 and provide accurate angular adjustment of the support.

Rearwardly projecting portions 16 of the support 12 act as guides for a vertical reciprocated actuator member 17 having a hook 18 at its upper end. Upon indication of weft exhaustion, a latch 20 having a hook-shaped lower end (not shown) is moved into operative relation with the hook 18, such movement being caused by an arm 21 pivoted at 22 on a bar 23 also mounted for vertical movement and having a lost motion connection with the actuator rod 17.

A detector frame 25 is yieldingly secured to the front side of the support 12 by fastening devices not shown, and is provided with a plurality of parallel slots or grooves in which detecting members or plungers 26 are slidably mounted. These plungers are reduced in thickness at their rear end to provide rounded portions 27 adapted to enter the holes in a bobbin when the weft is substantially exhausted thereon.

A tension arm 28 is pivotally mounted on a stud 29 at the front of the frame 25 and is engaged by the upwardly extended end of a spring 30 as shown in Fig. 2. The arm 28 yieldingly engages lugs 31 (Fig. 1) on the front ends of the plungers 26. Whenever any one of the plungers is engaged by a bobbin or by a substantial amount of weft thereon, the plunger is moved forward or to the right in Fig. 1 and the arm 28 is also yieldingly moved forward.

If one of the plungers, however, remains in rearward position, its lug 31 will be in the path of a portion 32 of the arm 21 as the sliding bar 23 descends, and the arm 21 will swing upon its pivot 22 to move the latch 20 into the path of the hook 18. The latch 20 is directly connected with the trans-ferrer and a change of bobbins will immediately follow.

A cover plate 33 is provided for the frame 25, being slidably secured thereto by depending side flanges having inturned lower edges. Rearward displacement of the plate is prevented by abutments 25^a formed on frame 25. A stud 34 extending from the

plate 33 extends through slot 35 formed in a link 33^a, the forward end of which is connected through stud 36 to an arm 36^a rigid with the transerrer lever. Through these 5 connections the plate 33 moves forward at transfer and by engaging lugs 31 withdraws all the detector plungers from the path of the incoming bobbins.

The parts thus far described are substantially of the form shown in the prior 10 patent to Ryon above noted, to which reference is made for a more complete description. These parts in themselves constitute no part of my present invention which relates to the provision of frictional resistance 15 for the different plungers 26.

For this purpose, I have provided a friction plate 40 (Figs. 3 and 4) riveted or otherwise secured to the cover plate 33 and 20 having a plurality of spring fingers 41 extending through the slot or opening 42 in the cover plate and yieldingly engaging the upper edges of the detecting plungers 26.

While I have shown my improved friction 25 device as mounted on the cover plate 33, it will be understood that this particular position of the plate is not essential and that it may be secured to the frame 25 if so desired.

With my improved tension or friction device 30 in use, the plungers 26 are at all times frictionally engaged. Such engagement by the spring fingers 42 yieldingly resists or retards movement of the plungers so that they are not readily displaced when they 35 are slightly engaged, as by a single turn or two of weft on the bobbin. The device is thus supplementary in its action to the spring arm 28 and the friction is of such character that it does not interfere with the 40 return movement of the plungers by the spring arm.

Having thus described my invention and

the advantages thereof, I do not wish to be limited to the details herein disclosed otherwise than as set forth in the claims, but what 45 I claim is:—

1. In a weft detecting mechanism, a plurality of elongated movable plungers, a single yielding device engaging said plungers and effective to return all of said plungers to normal rearward position, and additional means to resist longitudinal weft-indicating displacement of separate plungers in every position of said yielding device. 50

2. In a weft detecting mechanism, a plurality of elongated movable plungers, a single yielding device engaging said plungers and effective to return all of said plungers to normal rearward position, and additional means effective to separately apply friction 55 to each of said plungers and to thereby resist longitudinal weft-indicating displacement of separate plungers in every position of said yielding device. 60

3. In a weft detecting mechanism, a 65 frame, a plurality of plungers slidable therein, a yielding member engaging said plungers at their forward ends, a cover plate for said frame, and a plurality of spring fingers mounted on said cover plate 70 and yieldingly engaging said plungers to frictionally retard movement thereof.

4. In a weft detecting mechanism, a frame, a plurality of plungers slidable therein, a yielding member engaging said 75 plungers at their forward ends, a cover plate for said frame, and a spring plate mounted on said cover plate and comprising a plurality of separate spring fingers each frictionally engaging a separate plunger to 80 resist displacement thereof.

In testimony whereof I have hereunto affixed my signature.

WALTER H. WAKEFIELD.
